UNITED STATES PATENT OFFICE.

ORVILLE R. NOBLE, OF GRANVILLE, MASSACHUSETTS.

DESIGN FOR A DRUM.

SPECIFICATION forming part of Design No. 27,155, dated June 1, 1897.

Application filed March 29, 1897. Serial No. 629,870. Term of patent 7 years.

To all whom it may concern:

Be it known that I, ORVILLE R. NOBLE, of Granville, in the county of Hampden and State of Massachusetts, have invented and 5 produced a new and original Design for a Drum, of which the following is a full, clear, and exact description.

Reference is to be had to the accompanying drawings, forming a part of this specification, in which—

Figure 1 is a perspective view of a drum, showing my design. Fig. 2 is an enlarged transverse section of part of the drum-body on the line 2 2 of Fig. 1, and Fig. 3 is an enlarged side elevation of part of the drum.

My design forms an integral part of the drum-body band; and its leading feature consists in a flag A, of stars and stripes in relief and of a color or colors contrasting with the 20 color of the body-band, the stripes D being separated by narrow divisional lines E, following the lines of the stripes D and contrasting with the same.

Another feature of the design consists in the pronounced relief-border B and staff C 25 for the flag, as plainly indicated in Fig. 1.

A minor feature consists in ornamenting the drum-body band with flags A in pairs and with the relief-staffs C inclined toward each other, as shown, and with the relief-cords F and tassels G ornamenting the space between the staffs.

Another minor feature consists of parallel rows of beads H, which divide the drum-body band into longitudinal panels, of which the 35 middle one is ornamented by the ornamental flags A above described.

I claim—

The design for a drum as herein shown and described.

ORVILLE R. NOBLE.
